TREATING HYDROCARBON DISTILLATES

Charles Wirth, III, Chicago, Ill., assignor to Universal Oil Products Company, Chicago, Ill., a corporation of Delaware

Application March 31, 1939, Serial No. 265,069

12 Claims. (CL 196—40)

This invention is particularly concerned with the treatment of motor fuel obtained by cracking of heavy oils from petroleum or from the primary distillation of shale oil, coal tar, etc.

5 Practically all petroleum distillates of gasoline boiling range require some form of treatment to render them of marketable quality. Among the methods which have been used is the sulfuric acid treating method for improving color, reducing sulfur content, and improving storage 10 stability of cracked gasolines. Another method makes use of the refining effects of adsorbent materials using natural earths of the clay type, such as fuller's earth, which may or may not be 15 activated by chemical treatment. The refining action of the so-called clay treating process is carried out with the gasoline in either vapor or liquid phase depending on the temperature and 20 pressure conditions used. This method has wide application, particularly in connection with gasolines of low sulfur content. It is with improvements in this type of process that the 25 present invention is concerned.

In one specific embodiment my invention comprises fractionating the vaporous products from 25 a cracking process into a distillate of substantially gasoline boiling range, separately accumulating a portion of said distillate to use as reflux material in said fractionation step, treating 30 said reflux condensate with an acidic substance, such as dilute mineral acid, separating and returning it to the fractionating column, passing 35 the total products of distillation to a clay treating step operated under treating conditions, and recovering the finished gasoline.

Certain distillates resist treatment with adsorbent refining agents so that low yields of 40 finished gasoline per unit weight of treating reagent are obtained, and the process is not economical. Formerly such distillates were treated with sulfuric acid, but since the specifications for gasolines have changed in recent years, the 45 more severe acid treatment is no longer required in many instances. Its use with certain distillates has been continued by many refiners, however, because no other economical method was available and these distillates required treatment in some form before they could be marketed. It has been found that the treatment 50 of such refractory gasolines with dilute acid or other acidic substances prior to the clay treating step results in improvement in yields to an extent such that the operation becomes of a practical nature. The preferred reagent comprises dilute sulfuric acid, normally of 1-20%

concentration, although other mineral acids, acid sulfates, and solutions of heavy metal halides may be used satisfactorily by varying the treating conditions somewhat. The treated distillates may or may not be neutralized prior to the clay 5 treating step. This particular method of operation has resulted in improvements, but has one disadvantage in that the entire distillate must be condensed, subjected to the acid treating step, and then reheated to the desired treating 10 temperature for the clay treating step. This is disadvantageous when the vapor phase clay treating process is employed, since one of the advantages of vapor phase clay treating lies in the fact that gasoline vapors are treated directly 15 from the main fractionator of the cracking plant. The improvement of the present invention comprises the method for realizing the advantages of both acid pretreatment and vapor-phase clay 20 treatment.

In the fractionation it is necessary to return a portion of the overhead distillate to the top of the fractionator as reflux to assist in controlling the top temperature of the fractionator and the end point of the product being taken overhead. The portion of the product which is used as reflux varies in quantity from equal parts to 25 approximately four times the amount of distillate which is actually taken overhead, depending on the composition of the material being fractionated and upon the design of the fractionating equipment. The reflux condensate must be cooled and pumped in liquid form to the top of the fractionator in order to obtain the desired 30 result. It is possible to effect considerable improvement in the treating operation by contacting this reflux condensate, which amounts to 35 50-75% of the total product, with dilute acid prior to returning it to the fractionation step, and as a consequence, extend the life of the 40 adsorbent earth in the treating tower materially. At the same time it is not necessary to supply additional cooling or heating to the gasoline beyond that which is normally used in the fractionation step alone. The amount of treatment 45 obtained in this way is sufficient to improve the life of the clay at no additional cost beyond the chemicals used and the equipment necessary to carry out the pretreatment.

The amount of acidic solution used is dependent 50 to a certain extent on the concentration of the treating solution and may vary from 1-10% or more by volume of the distillate. The concentrations of the acidic substance are normally less than 20% although this varies with the solu- 55

- tion being used. For example, when using sulfuric acid solution strengths of 1-20% or even 30% acid or higher may be used, although normally the acid strength should be kept below that at which sludge formation occurs. Phosphoric acid may be used in similar concentrations. Hydrochloric acid should be used in concentrations of less than 10% in order to avoid undesirable chlorination of the gasoline.
- 10 The clay treatment may be carried out in any suitable apparatus employing temperatures of 250-600° F. and pressures of substantially atmospheric to 100 pounds when employing the vapor phase process. The treated gasoline may 15 or may not require fractionation in order to produce an end point product. The steps of treating with clay and recovering the treated gasoline are well known and need not be discussed in detail.
- 20 The attached diagrammatic drawing shows one embodiment of the invention. No attempt has been made to proportionate the various parts of the apparatus and no scale has been used in the drawing. The process should not be interpreted as being restricted to the exact equipment or flow given.
- 25 The vapors from the cracking plant enter the fractionator through line 1 and valve 2, passing into the main fractionator 3 where the heavy 30 recycle oil is withdrawn through line 4 and valve 5 and returned to the cracking plant. According to the preferred method of operation the gases and the vapors of substantially gasoline boiling range leave the top of the fractionator 35 through line 6 and pass through line 7 and valve 8. A portion of the vapors then are passed through line 9, valve 10, and condenser 11, line 12 and valve 13 into the reflux accumulator 14. From thence it is withdrawn through line 15, 40 valve 16 by means of pump 17, valve 18 into the acid washing system 19. The acid solution enters the plant through line 20 and valve 21 and the spent solution is withdrawn from the acid washer through line 22 and valve 23. The acid 45 washing system may comprise any suitable arrangement but is preferably of the countercurrent type whereby maximum use of the acid is obtained. Furthermore, the partially spent acid may be recirculated if desired by means not 50 shown. The gasoline leaves the system through line 24 and valve 25 and may pass through valve 26 into neutralizer 27 where it may be washed with water or with an alkaline solution to remove 55 any residual acid remaining. In this case the neutralized gasoline passes out through line 28 and valve 29 to line 30 and passes thence to the top of the fractionating column as reflux. In this case the water or neutralizing solution enters the plant through line 31 and valve 32 and line 33 which joins with line 24. The spent 60 solution may be withdrawn through line 34 and valve 35. As in the case of the acid washer any suitable apparatus may be used for this purpose and the neutralizing solution may be recirculated by means not shown. In some cases the neutralization step can be dispensed with. In this case the neutralizer is by-passed by means of line 33, valve 36 and line 37 which joins with line 30. Gases which are separated in reflux 65 accumulator 14 may be withdrawn from the receiver through line 38 and valve 39, or if desired they may be passed together with the gasoline into the clay treating system by means of line 40 and valve 41 which joins with line 42. The portion of the distillate which is not passed

to the reflux accumulator passes through line 42 and valves 43 and 44 to treating tower 45 where it is suitably treated with an adsorbent material such as fuller's earth. The treated mixture leaves the treating system through line 46 and valve 47. The finished gasoline is separated from the residual gases and the high boiling polymers formed during the treating step and condensed by means not shown.

As an alternative operation a light overhead 1 distillate may be withdrawn from the fractionator through line 7, valve 8, line 42 and valves 43 and 44 directly to the treating tower. The heavy portion of the gasoline is taken through line 48 and valve 49, a portion passing 1 through line 42 and valve 43 to the treating system, while the remainder which is to be used as reflux condensate is passed through line 9, valve 10 and routes previously described through the acid treating step, and returned as reflux 2 condensate to the top of the fractionator.

In still another alternative a side cut is withdrawn through line 48 and valve 49 as just described, and a light overhead fraction is taken through lines 6 and 50 and valve 51. In certain 2 instances this fraction requires no treatment and may be blended directly with the finished treated gasoline. In other cases a light treatment with the dilute acid may be given the low boiling fraction in a separate acid washing system which 31 is not shown but which may be similar to the one used for the reflux condensate.

It is oftentimes the practice when treating by the vapor phase clay method to remove distillate from the fractionator with a somewhat higher 31 end point than the finished gasoline. The end point of the gasoline is then adjusted by the fractionation step wherein the polymers are separated following the clay treatment. Since the gasoline is to receive a final fractionation 41 for adjusting the end point, it is not necessary that the fractionation in the main fractionator be as exact as might otherwise be the case. This makes possible the alternative methods described above wherein a naphtha side cut is used 41 as reflux material in the fractionator.

The following example is given to illustrate the usefulness of the process and should be construed as demonstrating its practicability and proving its usefulness but should in no way be interpreted as limiting it to the exact condition given therein.

The gasoline produced when cracking a California crude oil was fractionated and treated as described according to the preferred method in 55 the foregoing specifications. The end point of the overhead material from the main fractionator was approximately 420° F. and a reflux ratio of approximately 3:1 was used. This means that 3 parts of reflux condensate were collected, treated 60 with dilute acid, condensed and returned to the top of the fractionating column, to 1 part of gasoline passed to the clay treating system. The reflux condensate was treated with 2½% by volume of 10% sulfuric acid, separated and washed 65 with 5% of 5% sodium hydroxide solution and returned to the fractionator. The total mixture of reaction products from the clay treating step was fractionated to produce a 400° F. end point gasoline. In this manner a yield of 2300 barrels 70 of gasoline having a 25 color, oxygen bomb induction period of 150 minutes and 25 mg. of copper dish gum per 100 cc. was produced per ton of clay. The induction period of the gasoline was increased to 355 minutes and the gum lowered to 75

5 mg. by the addition of 0.0025% of a commercial inhibitor. By running to a color of 21° Saybolt the yield obtained was increased to 3800 barrels per ton of clay. When operating on this particular distillate in the usual manner without the pretreatment of the reflux condensate a yield of only 900 barrels per ton of clay was obtained. Fuller's earth was used as the treating reagent and the gasoline was contacted at a temperature of 450° F. and 50 pounds per square inch pressure at the inlet to the clay tower.

I claim as my invention:

1. A process for refining hydrocarbon distillate which comprises fractionating said distillate into a fraction of substantially gasoline boiling range, collecting a portion of said gasoline as reflux condensate, treating said condensate with an acidic refining agent and returning it as reflux to the fractionator, passing a portion of the fractionated gasoline vapors to a refining step and therein contacting the same with an adsorbent refining agent, and recovering the refined gasoline.

2. The process of claim 1 wherein the ratio of reflux condensate to gasoline passed to the adsorbent refining agent is between the limits of approximately 1:1 and 4:1.

3. The process of claim 1 wherein the second-mentioned refining agent is an adsorbent clay.

4. The process of claim 1 wherein the acidic refining agent is a mineral acid.

5. The process of claim 1 wherein the acidic refining agent comprises essentially sulfuric acid.

6. A process for refining gasoline which comprises fractionating said gasoline into high and low boiling fractions, recovering said low boiling fraction without further refining, contacting a portion of said high boiling fraction with an adsorbent refining agent, accumulating another portion of the high boiling gasoline fractions from the fractionating step, condensing and contacting said accumulated gasoline with an acidic refining agent, separating it, and then returning it to the fractionating step as reflux, continuously withdrawing the products from the adsorbent treating step, and recovering the gasoline therefrom.

7. A process for refining gasoline which comprises fractionating said gasoline into low and high boiling fractions, contacting said low boiling fraction and a portion of said high boiling fraction with an adsorbent treating reagent, recovering the gasoline therefrom, accumulating another portion of said high boiling gasoline fraction from the fractionating step, condensing and contacting it with an acidic refining agent, and separating and returning the thus treated oil to the fractionating step as reflux.

8. A refining process which comprises fractionating hydrocarbon vapors containing gasoline and heavier hydrocarbons to separate the gasoline from heavier hydrocarbons, passing a portion of the gasoline in vapor form from the fractionating step to a refining step and therein contacting the same with an adsorbent refining agent, treating another portion of the gasoline from the fractionating step with an acidic refining agent and thereafter returning it in liquid form to the fractionating step as a refluxing medium therein.

9. A refining process which comprises fractionating hydrocarbon vapors containing gasoline and heavier hydrocarbons to separate the gasoline from heavier hydrocarbons, removing the separated gasoline from the fractionating step in vapor form, contacting a portion of the gasoline vapors with an adsorbent refining agent, condensing another portion of the gasoline vapors and treating it with an acidic refining agent, and returning the thus treated condensed gasoline to the fractionating step as a refluxing medium therein.

10. A refining process which comprises fractionating gasoline-containing vapors to form a light vaporous gasoline fraction and a condensate containing heavier gasoline fractions, contacting said vaporous fraction with adsorbent clay, treating said condensate with an acidic refining agent and thereafter returning it to the fractionating step as a refluxing medium therein.

11. A refining process which comprises fractionating hydrocarbon vapors containing gasoline and heavier hydrocarbons to separate the gasoline from heavier hydrocarbons, passing a portion of the gasoline in vapor form from the fractionating step to a refining step and therein contacting the same with adsorbent clay, treating another portion of the gasoline from the fractionating step with a dilute mineral acid solution and thereafter returning it in liquid form to the fractionating step as a refluxing medium therein.

12. A refining process which comprises fractionating hydrocarbon vapors containing gasoline and heavier hydrocarbons to separate the gasoline from heavier hydrocarbons, passing a portion of the gasoline in vapor form from the fractionating step to a refining step and therein contacting the same with adsorbent clay, treating another portion of the gasoline from the fractionating step with a dilute sulfuric acid solution and thereafter returning it in liquid form to the fractionating step as a refluxing medium therein.
